UNITED STATES PATENT OFFICE.

MITCHELL T. CHANCY, OF EDDYVILLE, ILLINOIS, ASSIGNOR OF ONE-HALF TO THEOPHILUS MORSE AND ANDREW J. NESSELRODT, OF GOLCONDA, ILLINOIS.

SAW-KNIFE.

SPECIFICATION forming part of Letters Patent No. 585,157, dated June 22, 1897.

Application filed December 31, 1896. Serial No. 617,668. (No model.)

To all whom it may concern:

Be it known that I, MITCHELL T. CHANCY, a citizen of the United States, residing at Eddyville, in the county of Pope and State 5 of Illinois, have invented certain new and useful Improvements in Saw-Knives; and I do declare the following to be a full, clear, and exact description of my invention, such as will enable others skilled in the art to 10 which it appertains to make and use the same.

My invention relates to improvements in the class of saws and knives used by butchers and grocerymen in the preparation of meats for market and by butlers and cooks in carving 15 for the family table.

The improvement is embodied in the relative construction and arrangement of parts, as hereinafter described, whereby I produce a simple, compact, cheap, durable, and easily- 20 adjustable saw or knife which is effective for its purpose and embodies these two very necessary utensils in the same framework and handle.

In the accompanying drawings, Figure 1 is 25 a perspective view of my improved combination saw-knife, showing the blade resting loosely between the pivot centers. Fig. 2 is an enlarged view showing fulcrum centers and locking device. Fig. 3 shows detail 30 views of pivot-pins and locking device.

The chief parts of my combination saw-knife are a framework A, a handle B, a blade C, having saw and knife edges, respectively, a pivot-pin D, locking devices E F, and the 35 fulcrum-screw G. The aforesaid blade C is preferably tapering in shape, as shown, with a V-shaped cut-away portion in its smaller end to form pointed ends for the saw and knife, but any other desired construction 40 may be used without materially altering the effectiveness of the device.

A represents the framework of my device, which is bent, as shown, to fit closely about the blade, affording protection to the user 45 against injury from the edge not in use and forming supports for its pivoted ends. To this framework is riveted a handle B of the ordinary construction.

The blade C, which may be made of steel

or other suitable material, is provided with a 50 series of teeth of the customary size for meat-saws on one edge, while the opposite edge is sharpened to form a suitable knife-blade.

D represents a pivot-pin which is riveted to the large end of the blade at the center and 55 has a projecting end which passes through an aperture d^2 in the framework and forms a pivotal bearing for one end of the blade, being securely fastened into position by the thumb-screw d' , which engages in the inner threaded 60 portion of the said pin.

F represents a locking-pin of the construction shown, having a threaded end for the engagement of the knob f' and a cut-away portion to form a butt for the reception and 65 engagement of the spiral f^2 , whose opposite end rests against the butt f^3 , formed in the framework, and thus acts to force the locking-bolt into the hole e' formed in the projecting butts E, which are riveted at the corners of 70 the blade, as shown. A similar butt G is riveted to the opposite end of the blade at the center of the V-shaped notch and serves to protect that portion of the blade and affords a means for the engagement of the fulcrum-screw g' , which is partly threaded for engagement in the correspondingly-threaded portion 75 of the frame at g^2 , and thus forms a pivot-bearing for that portion of the blade.

Having thus described my invention, what 80 I claim, and desire to secure by Letters Patent, is—

In a saw-knife, a reversible blade provided with a pivotal support at each end, two sockets at its inner end, and two points at its outer 85 one, combined with a frame in which the blade is pivoted, and which has its front end turned backwardly in a line with the blade so as to form a support for the front end of the blade in between its two points, and a 90 stop for locking the blade in any desired position, and which engages alternately with the sockets, substantially as described.

MITCHELL T. CHANCY. [L. S.]
